UNITED STATES PATENT OFFICE

LLOYD J. TAYLOR, OF WICHITA FALLS, TEXAS, ASSIGNOR TO TAYLOR FOUNDRY COMPANY INC., OF WICHITA FALLS, TEXAS

LOCK FOR METER BOX COVERS

Application filed March 24, 1931. Serial No. 524,884.

This invention relates to meter boxes and is has particular reference to new and useful improvements in lock covers therefor and the principal object of the invention resides in a lock for cover for meter boxes and the like having the maximum simplicity and consequent low manufacturing cost.

Another object of the invention resides in the provision of an improved gravity locking arrangement of such design that the lid proper will require no reinforcing means whatsoever and further, a fulcrum diametrically opposite the lock of such peculiar design as to hold the cover in raised position, yet allowing the cover to fall into locked position and be so locked without the aid of the key.

Still another object of the invention resides in the fact that the improved lock cover may be produced in its complete form with but a single moving element and requires no springs or other analogous elements to aid in its operation.

With the foregoing objects as paramount, the invention has particular reference to its salient features of construction and arrangement of parts which will become manifest as the description proceeds, taken in connection with the accompanying drawing, wherein:

Figure 1 is a side elevational view of the invention.

Figure 2 is a perspective view of the underside of the improved meter box cover.

Figure 3 is a fragmentary view partly in section showing the improved fulcrum.

Figure 4 is another perspective view, fragmentarily showing the cover and flange and illustrating in detail the relationship between the gravity locking element and key, and

Figure 5 is a detail view showing the gravity locking element in solid lines in operative position and depicting the same in dotted lines in the position to which it is moved by the key.

Continuing more in detail with the invention, 1 designates a circular flange having a series of lugs 2. In ordinary practice, the meter box, which is not herein shown, is constructed of metal or concrete and in order to secure the flange 1 thereto, a wire is passed

through the aperture in the lugs 2 and either embedded in the concrete fabrication of the meter box or affixed in some suitable manner to the metal type of box so that the flange 1 is movable relative to the box.

The flange 1 is annularly recessed to provide a seat for the disc-like lid or cover 3 which as apparent in Figures 2 and 3 has a projection 4 integral therewith, which projection is received in a recess *a* in the flange 1 and is bifurcated as at *b* to receive a pin 5.

A slot *b* is of such peculiar shape that when the lid 3 is raised, it will lie on an inclined plane and will thus be kept from falling.

Referring now to the means by which the lid or cover 3 is held in locked relationship with the flange 1, it will be noted that a pair of ears 6 are integral with and depend from the underside of the lid 3. These ears or lugs 6 are joined together by an intermediate web 7, the purpose of which is apparent in Figure 5 and will be again referred to presently. The gravity locking element 8 has a lobe *c* which normally lies in the position shown in solid lines in Figure 5 and assumes this position by reason of the weighted portion defining the lobe *c*. The member 8 is pivotally mounted on the pin 9 extending through the ends of the ears or lugs 6 so that the member may be rocked to and fro to move the member into and out of locked position as shown in Figure 5.

Also integral with the gravity locking member 8 is a cam surface 10, which is offset relative to the weighted lobe *c* yet is an integral part of the said member 8. It is against this cam surface 10 that the lug 11 of the key 12 impinges and the peculiar shape of the cam surface 10 is such that frictional rotation of the key lug 11 against the curved surface of the cam 10 will function to displace the lobe *c* from its position under the shoulder *d* of the flange 1, and bring the same to the position shown in dotted lines in Figure 5. The relative position of the lug 11 of the key 12 is also shown in dotted lines in this figure.

Thus the member 8 is moved to unlocked position by manipulating the key 12 to actuate the lug 11 which is insertable through a correspondingly shaped aperture 13 in the cover

3, beneath which is a ward or box 14. The cover 3 may then be raised on the pivot 5 diametrically opposite the lock where it may rest at an incline until a reading or the meter is taken, whereupon the cover may then be dropped again to its position shown and since the lug *c* is of greater weight than the lower portion of the locking member 8, it will fall outward and due to the annular face *e* of the member 8, it will readily slide over the shoulder *d* of the flange 1 and assume the locked position shown in Figure 5 in solid lines until the key 12 is again inserted to repeat the operation.

15 As referred to previously, a web 7 joining the lugs 6, as clearly shown in Figure 5 is engaged by a portion of the cam 10, thus affording a stop to limit the outward movement of the weighted portion *c* of the locking member 8. Due to the presence of the stop 7, the gravity locking member is constrained to lie in a predetermined plane so that when the lug 11 of the key 12 is brought into relative contact with the cam 10, there will be no binding action and the unlocking operation may be carried out with the same ease and readiness in all cases. When the lug 11 is rotated against the cam 10, the lobe *c* or weighted portion of the member 8 is moved toward the key and is thus displaced from its position under the flange 1.

It is particularly important to note that the elements of the combination with the exception of the locking member 8 may be cast 35 in one operation, which is a desideratum for economical construction and further, since no ribs or other reinforcing means are required, which is a further aid in reducing the cost of production and this, together with 40 the fact that but a single movable element is embodied in the structure, produces not only an economical construction, but one which will meet all requirements as to durability and ease in the performance and operation.

45 Manifestly, the construction shown is capable of some modification and such modification as is considered within the scope and meaning of the appended claims is also considered within the spirit and intent of the invention.

What is claimed is:

1. A lock for meter box covers including a weighted member carried by said cover and normally lying beneath the edge of the support for said cover and a cam extending at right angles from said weighted member against which a key is urged to rock said weighted member to a position to escape the edge of said support to effect removal of said 55 cover from said flange.

2. A lock for meter box covers including a support integral with the underside of said cover comprising a pair of depending ears and a web intermediate the said ears, a stub 60 shaft shaped to define a cam axially pivoted

between said ears and having a stop engaging the web between said ears, a weighted portion integral with said stub shaft normally reposing by gravity under the edge of the support for said cover whereby to maintain said stub shaft in position to present a surface against which a key bit may be rotated to move said weighted portion to disengage the cover from its support.

3. A lock for meter box covers including a stub shaft defining a cam surface suspended below said cover and having an integral weighted member normally extending beyond the edge of said cover by gravity, a stop also integral with said stub shaft to hold said weighted member in predetermined extended position and to hold the cam surface of said stub shaft in a position to receive the contact of the bit of a key rotated thereagainst whereby to move said weighted portion within the diameter of said cover.

4. A lock for meter box covers including a pair of ears integral with and depending from said cover adjacent its edge and having an intermediate web defining a stop, a stub shaft having its ends pivoted in apertures in said ears and having a body shaped to produce a gradual slope from one end to the other, said shaft further having an appendant at right angles thereto and whose upper end is of greater weight than its lower end whereby to normally repose outside of the diameter of said cover preparatory to its withdrawal by an instrument frictionally moved against the slope of said body.

5. A lock for meter box covers including a stub shaft having a body shaped to define a gradual slope from one end to the other and further having an appendant integral therewith whose axis is at right angles to the axis of said shaft whereby its upper end will normally lie beyond the diameter of said cover, preparatory to its withdrawal by a key moved against the slope of said body.

In testimony whereof I affix my signature.

LLOYD J. TAYLOR.
